No. 845,453.

PATENTED FEB. 26, 1907.

C. C. ELLIOTT.

LOCATING GAGE FOR SEWING MACHINES.

APPLICATION FILED JUNE 7, 1904.

UNITED STATES PATENT OFFICE.

CHARLES C. ELLIOTT, OF TROY, NEW YORK, ASSIGNOR OF ONE-HALF TO
UNITED SHIRT & COLLAR COMPANY, A CORPORATION OF NEW YORK.

LOCATING-GAGE FOR SEWING-MACHINES.

No. 845,453.

Specification of Letters Patent.

Patented Feb. 26, 1907.

Application filed June 7, 1904. Serial No. 211,454.

To all whom it may concern:

Be it known that I, CHARLES C. ELLIOTT, a citizen of the United States of America, and a resident of Troy, county of Rensselaer, State of New York, have invented certain new and useful Improvements in Locating-Gages for Sewing-Machines, of which the following is a specification, reference being had to the accompanying drawings, forming a part thereof.

My invention relates to improvements in sewing-machine attachments, and particularly to means arranged in connection with a sewing-machine for locating or positioning the article to be operated upon.

My device is preferably made in the form of an attachment which may be readily secured to existing forms of sewing-machines and in the preferred form is further so constructed that it may be turned out of the way when not in use.

The main object of my invention is to provide means whereby the position of the material to be operated upon may be quickly and accurately determined, so that the material may be readily inserted in proper position in the work-clamp; and to this end my invention consists in providing a locating means and suitable adjustments therefor, so that the said locating means may be properly positioned with respect to the stitching mechanism of the sewing-machine.

My invention also consists in providing the device with a suitable graduated scale, so that the proper position of the locating means with respect to the stitching mechanism or work-support may be quickly determined in an improved construction, whereby the device may be readily thrown out of position when not required to be used, and in certain novel details of construction and combination of parts, as will hereinafter more fully appear.

I will now proceed to describe a device embodying my invention and will then point out the novel features in claims.

In the drawings, Figure 1 is a top view of a gage embodying my invention, showing the same secured to the bed of a sewing-machine and showing certain portions of the sewing-machine, including portions of the work-clamp. Fig. 2 is a view in vertical longitudinal section through the gage. Fig. 3 is a vertical transverse section therethrough, the

plane of section being taken substantially upon the line 3 3 of Fig. 1. Fig. 4 is a top view of the locating means removed from its carrier. Fig. 5 is a top view in detail of certain parts of the gage, showing a different form of locating device employed and showing a piece of fabric engaged thereby. Fig. 6 is a view in vertical transverse section thereof, the plane of section being taken substantially upon the line 6 6 of Fig. 5.

The device herein may be employed as a gage for locating many articles; but it is especially adapted for locating collars in button-hole-sewing machines when presented therein for the stitching of the central or back buttonhole. It is essential, of course, that this buttonhole be accurately positioned with respect to the end buttonholes, and heretofore a common practice has been to double over a collar and mark the center at the crease and to then locate the collar in the work-clamp by means of this mark. It will be readily understood that great inaccuracies often result from such a custom.

In the preferred form of my present device, and which form is shown in Figs. 1, 2, 3, and 4 of the drawings, I employ a locating means which actually engages the collar by entering one of the end buttonholes. It will then be seen that the said locating means being initially adjusted to a predetermined position the collar will always be accurately centered in the work-clamp. By then providing the device with a graduated scale, the graduations of which correspond to the difference between the standard size of collars, it will be readily seen that the simple adjustment of the locating means along the scale will be all that is necessary to accurately adjust the device for any size collar desired to be operated upon. I also preferably provide two other adjustments, one a compensating adjustment of the locating means with respect to the scale, so that when the device is first set in the machine the relationship of the scale with respect to the point of stitching may be properly determined, and the other a lateral adjustment for the device as a whole, so as to properly position the work laterally.

Referring first to Figs. 1, 2, 3, and 4, 1 designates a plate or clamp adapted to be secured to the bed 2 of a sewing-machine, to which it may be clamped by means of a screw 3, which passes through a slot 4 in the

said plate. The slot 4 permits the clamp or plate 1 to be moved laterally in order to laterally adjust same, the screw being employed for clamping it in the position to which it is adjusted. Preferably the front edge of the clamp or plate 1 is provided with a flange 5, which engages the front edge of the bed-plate 2 of the machine, whereby the plate may be prevented from turning. 6 designates a support pivoted to the clamp by means of a pivot-pin 7. A spring 9 bears against the said support to retain same in position, the said support being provided with a depending flange 8, which bears against the front edge of the bed-plate of the machine and acts as a stop. When the device is not intended to be used, the support 6 may be swung around upon its pivot 7 until it is at right angles to the position in which it is shown, when the spring 9 will engage the end face of an offset portion 10 of the support 6; the spring then retaining the support in its out-of-use position. The face of the support 6 is longitudinally channelled, and fitted to the said channel is a carrier 11. The carrier acts as a support for a pin or stud 12, constituting a locating means, as will presently be described. The pin or stud 12 is mounted on a plate 13, adjustably secured to the carrier 11 by means of a set-screw 14. The plate 13 is slotted, so as to permit some longitudinal adjustment of the locating means with respect to the carrier 11, supporting it. The carrier 11 is provided with a laterally-projecting pin 15, arranged to engage any one of a series of notches 16, formed as graduations of a scale denoted by reference character 17 as a whole. The carrier 11 has rigidly secured thereto a depending bolt or stud 18, the lower end of which carries a nut 19, between which and a washer 20, arranged against the under surface of the support 6, is located a compression-spring 21. The spring 21, which surrounds the stud 18, tends to hold the carrier 11 down in its seat in the channel in the support 6 and to hold the pin 15 into engagement with one of the notches 16 of the scale 17. The bolt or stud 18 projects through a longitudinal slot 22 in the support 6, and so in no way impedes the free movement of the said carrier along its support. When it is desired to adjust the carrier along the support from one position to another, the carrier is slightly lifted by pressing upward upon the bolt or stud 18, thereby releasing the laterally-projecting pin 15 from the notch 16 with which it was in engagement and permitting the carrier to be moved. The carrier may be moved to any desired position with the pin 15 resting in any desired notch. This last movement permits adjustment of the locating means toward and away from the work-clamp, so that the said locating-pin 13 may be properly positioned to present any predetermined

size collar for a buttonhole-stitching operation. When the device is initially set in a machine, it is sometimes necessary to compensate slightly for variations in width of bed-plate and in relative positions of the work-clamp with respect to the edge of the bed-plate, and for this reason I have provided the locating means with a compensating adjustment, so that it may be initially adjusted with respect to the scale-graduations. Thus the said graduations will be caused to properly correspond with the required position of the said locating-stud with respect to the point of operation of the work.

The style of work-clamp employed is entirely immaterial, and in the present instance I have shown the ordinary form of "National" work-clamp, employing a lower plate or work-support 23 and clamping-plate 24, supported by the forked presser-lever 25. For properly positioning the collar laterally I preferably provide a small angle-gage 26, secured to and carried by the plate 23, the lower edge of the collar being arranged to bear against the face of the said gage, as will be readily understood, in order to laterally position the collar, so that the buttonhole may be made the proper distance from the said lower edge. In Fig. 1 of the drawings a portion of the collar is shown in dotted outline in position for a buttonhole-sewing operation. One of the end buttonholes will be seen as engaged by the locating-pin 12 and the center of the collar in position in the work-clamp for a sewing operation. It will be readily seen that by causing the locating means to actually engage the end buttonhole of the collar mistakes in positioning of the collar will be reduced to a minimum, it being only necessary to properly adjust the position of the locating-pin to insure proper positioning of the collar.

For different classes of work I employ different forms of locating means. For instance, where a button has been sewed to a fabric I may employ a locating means which will engage the said button and so properly position the fabric to which it is attached for another button-sewing operation or a buttonhole-sewing operation or any other operation that may be desired. In Figs. 5 and 6 I have shown a locating-plate 27 as substituted for the locating pin or stud 12, the locating-plate 27 being adjustably secured to the carrier 11 exactly as is the plate 13 of the locating means above described, the said plate extending laterally for a short distance and then turning over and back again, so as to clear material passing between it, the end of the plate provided with a V-notch 28 and adapted to engage a sewed button, as shown in Figs. 5 and 6.

What I claim is—

1. In a gage for sewing-machines, the combination with a support arranged to be se-

cured to the bed of a sewing-machine, said support comprising a longitudinally-channeled member provided with a series of notches along one edge and having also a longitudinal slot therethrough, of a carrier fitted to said channel and arranged to slide longitudinally therein, said carrier provided with a laterally-extending finger arranged to register with said notches, a dependent stud secured to said carrier and arranged to project through the slot in said support, a spring surrounding said stud, and arranged between an abutment carried by the stud and the lower surface of the said support, and a locator comprising a stud for engaging a collar-button and a slotted plate to which said stud is attached, said slotted plate adjustably secured to the said carrier by means of a clamping screw engaging said carrier and passing through the slotted portion of the said plate.

2. In a gage for sewing-machines, the combination with a stud for engaging a collar-buttonhole, of a support for said stud upon which said stud is adjustably mounted, said

gage provided with an indicating-scale, the 25 graduations of which correspond to the difference between collar sizes, a clamp constructed for attachment to a sewing-machine bed and upon which the support is pivoted, and impositive spring-actuated locking means 30 between the clamp and the support.

3. In a sewing-machine, the combination with a clamp, and means for adjustably securing same to the bed-plate of a machine, of a support pivotally mounted on said clamp, 35 and spring-held in position thereon, said support provided with a scale, a carrier mounted on said support and longitudinally adjustable thereon with respect to said scale, and a locating device adjustably mounted on said 40 carrier.

In witness whereof I have hereunto set my hand this 3d day of June, 1904.

CHARLES C. ELLIOTT.
